CLAIM

The ornamental design for a chest, as shown and described.

DESCRIPTION

FIG. 1 is a front elevational view of a chest showing my new design;

FIG. 2 is a left side elevational view, the right side being
a mirror image thereof;

FIG. 3 is a top plan view thereof;

FIG. 4 is a bottom plan view thereof;

FIG. 5 is a rear elevational view thereof;

FIG. 6 is a perspective view of a modified form of the chest shown in FIG. 1 with the top and side doors in open position;

FIG. 7 is a front elevational view thereof; and

FIG. 8 is a left side elevational view, the right side being a mirror image thereof.
